Patented Oct. 19, 1920.

UNITED STATES PATENT OFFICE.

HERMAN GEORGE BENDIX AND PETER J. SPECCE, OF NEW YORK, N. Y.

SHOE CLEANING AND IRONING JACK.

1,356,425.

Specification of Letters Patent.

Patented Oct. 19, 1920.

Application filed February 6, 1920. Serial No. 356,756.

To all whom it may concern:

Be it known that we, HERMAN GEORGE BENDIX and PETER J. SPECCE, both citizens of the United States, and residents of the 5 city of New York, borough of Brooklyn, in the county of Kings and State of New York, have invented a new and Improved Shoe Cleaning and Ironing Jack, of which the following is a full, clear, and exact 10 description.

This invention relates to shoe machinery or apparatus, and has particular reference to jacks or supports for holding shoes, slippers or the like, for the purpose of finishing, cleaning, or dressing them.

Among the objects of the invention is to provide a shoe-holding jack that is adapted to directly receive and support a shoe when carried by any conventional last, the means 20 for holding the last and shoe thereon being easily operated both for locking the last in place and for the release thereof.

Another object of the invention is to provide a device of the nature set forth that is 25 the most convenient with respect to the manipulation of the shoe when supported thereon.

With the foregoing and other objects in view, but without unnecessarily limiting the 30 construction, the preferred embodiment of the invention is illustrated in the accompanying drawings, wherein similar parts are referred to in the several views by like reference characters, and in which—

35 Figure 1 is a side elevation of our invention indicating the manner of use thereof, dotted lines indicating a change of position of some of the parts and a portion of the supporting bracket being broken away.

40 Fig. 2 is a longitudinal horizontal section on the line 2—2 of Fig. 1.

Fig. 3 is a vertical transverse section on the line 3—3 of Fig. 1.

45 Fig. 4 is a fragmentary side elevation of the jaw portion of the jack but with the jaws omitted.

50 Referring now more specifically to the drawings, we show our improvement as comprising a strong rigid member which simulating in some respects the form of the human leg or ankle will be referred to hereinafter as the leg 10. This leg may be made of any suitable rigid material and includes at one end a round bearing or trunnion portion 11 provided with a circumferential groove 12, and having adjacent to the bear-

ing a shoulder 13. The bearing 11 is fitted into a fixed bearing sleeve 14 adapted to be connected by bolts 15 or their equivalent to any suitable upright support 16. A set 60 screw 17 is tapped through the side of the sleeve 14 and extends into the groove 12 of the leg bearing so as to hold the leg from slipping out of the sleeve, yet permitting the free rotation of the leg around the axis 65 of the bearing.

At L we show any suitable or conventional form of last upon which the shoe S is fitted, the last being provided as usual with a socket 18 to receive a stud 19 constituting a 70 rigid extension of the ankle portion 20 of the leg. As shown best in Fig. 4 the stud 19 extends outward and slightly downward from a bridge portion 21 which spans the upper and lower parts of the ankle end of 75 the leg. Between the upper and lower edge portions of the leg just referred to, there is formed the opening 22 extending lengthwise of the leg and practically all the way between the bridge and the shoulder 13, and 80 extending all the way through the leg laterally.

Located in the opening 22 and journaled upon vertical parallel pins or pivots 23 fitted in the upper and lower edges of the leg are 85 a pair of jaws 24, constituting levers of the first class. In other words, each jaw member at its outer end constitutes a gripping jaw 25 which is widened out and adapted to grip directly against the upper portion of 90 the last L, while the opposite portion of the jaw member or lever is bent inward slightly toward the central axis of the leg. (See Fig. 2.) The two jaws are similar in construction and the lever ends thereof are 95 spaced from each other but somewhat convergent, accommodating between them a wedge-shaped tightening member 26 movable longitudinally along the space 22.

A hand lever 27 projects downward 100 through a bottom opening 28 and is pivoted in said opening on the pivot 29. This also is a lever of the first class and had connected to its upper end in the space 22, a link 30. The link is pivoted at 31 to the lever 27 and at its other end to the wedge 26 at the point 32. A locking device in the form of a set screw 33 is tapped into one side of the leg so as to bear directly against the lever 27 to prevent undesired movement of such lever 110 around its pivot 29.

The opening 22 extending along the leg

is substantially filled or covered by means of face plates 34 fitted flush therein upon rabbets 35. These face plates extend forward so as to cover nearly all of the jaw members but leaving the gripping portions free for action.

The bridge 21 is provided with a transverse hole 36 in which is located an expansion coil spring 37 the ends of which bear 10 outward against the jaws 25, tending to force them apart.

With the foregoing specific description of the mechanism, its mode of operation and advantages may be readily understood 15 through the following brief summary.

In the idle position of the device, the hand lever 27 occupies the dotted line position of Fig. 1, the wedge 26 being moved forward releasing the jaw levers and permitting the spring 37 to throw the jaws 20 apart so that the last L may be slipped freely upon the stud 19 as shown. The operator then positioned adjacent to the shoe or last, grasps the lever 27 and draws it 25 forcibly toward him, as shown in full lines. This action draws the locking member or wedge 26 in the opposite direction, causing the wedge thereof to force the convergent ends of the levers apart and the jaw members 30 into gripping action upon the last. The ordinary disposition of the locking device will be maintained by friction, but to obviate any possible accidental loosening thereof, the set screw 33 may be tightened 35 to prevent movement of the lever 27, and as long as the lever is held from movement around its pivot, the locking wedge will maintain the jaws in holding position. With the parts adjusted as just described, the 40 shoe fitted to the last will be in position for the most convenient treatment such as finishing, cleaning, washing, pressing, or dressing, and furthermore if it is a shoe with an upper, the upper may be laced or

otherwise fastened around the ankle portion 45 of the leg 10 if desired in order to treat it. While the operation is in progress, the entire leg and parts carried thereby may be rotated around the axis of the bearing 11 if desired to afford complete access to all 50 parts of the shoe.

We claim:

1. The herein described shoe jack comprising a leg having a longitudinal space therein terminating at one end in a bridge, a 55 last holding stud extending outward from the bridge, means acting upon the last while so supported to prevent its undesired removal from the stud, and means within the longitudinal leg space serving to lock the 60 last holding means.

2. In a shoe jack the combination of a leg having a longitudinal opening therein, a pair of jaws fitted in said opening, locking means for the jaws extending along the 65 same in the opening, and hand means to operate the locking means.

3. In a shoe jack the combination of a rigid leg having a longitudinal opening 70 therein bounded at one end by a bridge having a transverse hole, a pair of last holding jaws pivoted in the leg and extending along said opening on opposite sides of the bridge, means located in said hole tending to force the jaws apart and other means acting upon 75 the jaws tending to cause them to approach each other against the force of the means in the hole.

4. In a shoe jack the combination of a rigid leg, means to support the leg for rotation around a longitudinal axis, last holding means at one end of the leg, a manually operated means to operate the last holding means, and means acting upon the manually controlled means to prevent unintentional release thereof.

HERMAN GEORGE BENDIX.
PETER J. SPECCE.
